UNITED STATES PATENT OFFICE.

RICHARD W. OSWALD, OF SEWICKLEY, PENNSYLVANIA.

FAN WHEEL.

Application filed August 24, 1921. Serial No. 494,825.

To all whom it may concern:

Be it known that I, RICHARD W. OSWALD, a citizen of the United States, residing at Sewickley, in the county of Allegheny and State of Pennsylvania, have invented a new and useful Fan Wheel, of which the following is a specification.

The device forming the subject matter of this application is a fan wheel, and one object of the invention is to provide a fan wheel wherein the constituent parts need not be tied together by rods, spiders, web plates, and the like, in order to keep the vanes or blades in position.

Another object of the invention is so to construct the wheel that, tapering the laterally projecting blades or vanes, the wheel will be of greatest diameter at the median plane of the wheel, the wheel being of lesser diameter at its ends, the result being that the wheel has a tendency to draw the air toward the center of the fan.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in elevation, a wheel constructed in accordance with the invention; Figure 2 is a cross section of the wheel; Figure 3 is a fragmental cross section showing a modification; Figure 4 is a fragmental cross section showing a further modification; and Figure 5 is a sectional detail showing another modification.

Referring to the wheel as shown in Figures 1 and 2, there is provided a body 1 in the form of a disk, located between hub parts 2, the hub parts 2 being attached to the body 1 by securing elements 3. The hub parts

2 are mounted on a shaft 4. Laterally projecting blades or vanes 5 are provided, the same being supplied with inner flanges 6 and with outer flanges 7. The inner flanges 6 abut against the body 1 and are connected thereto by securing elements 8. A ring 9 is connected to the flanges 7 by the securing elements 10. As shown at 11, the blades taper from their inner ends toward their outer ends, the blades being widest adjacent to the body 1 and being of less width adjacent to their outer ends. As a consequence of the foregoing, the wheel is of greatest diameter in alinement with the body 1 and is of lesser diameter adjacent to its ends, that is, adjacent to the outer ends of the blades 5. The wheel, constructed as above described, has a tendency to draw the air to the center of the wheel, since the velocity or rim speed is greater adjacent to the median plane of the wheel than at its ends. The general makeup of the wheel is such that it will have the requisite strength without resorting to tie rods and other elements of a like sort, commonly used in the making of fan wheels.

In Figure 1 of the drawings, the blades 5 are shown as being straight, whereas, in Figure 5, the blades 5^a are dished slightly, the body of the wheel appearing at 1^a, and the inner flanges being designated by the numeral 6^a.

In Figure 4, the body appears at 1^b and the ring at 9^b, the numeral 5^b denoting one of the blades. In this form of the invention, the inner edge 25 of the blade 5^b is disposed at right angles to the body 1^b, all of the taper being in the outer edge 26 of the blade 5^b.

In Figure 3, parts hereinbefore described have been designated by numerals previously, with the suffix "c." In this form of the invention, the outer edge 28 of the blade is at right angles to the body 1^c, all of the taper being in the inner edge 29 of the blade. This form of the invention does not possess the advantages of the other forms, but it may be resorted to if desired.

What is claimed is:

A fan wheel comprising a body and blades 100

projecting laterally from the body in opposite directions, the outer edges of the blades being inclined, from the body, toward the axis of rotation of the wheel, thereby to render the wheel of greater external diameter at its median plane than at its ends.

In testimony that I claim the foregoing

as my own, I have hereto affixed my signature in the presence of two witnesses.

RICHARD W. OSWALD.

Witnesses:

S. E. GREEN,
F. H. CZARNUCK.
